UNITED STATES PATENT OFFICE.

THOMAS WILLIAM COSGROVE, OF DOWAGIAC, MICHIGAN.

DESIGN FOR A BADGE.

SPECIFICATION forming part of Design No. 31,218, dated July 18, 1899.

Application filed October 14, 1898. Serial No. 693,558. Term of patent 14 years.

To all whom it may concern:

Be it known that I, THOMAS WILLIAM Cosgrove, a citizen of the United States, residing at Dowagiac, in the county of Cass and State of Michigan, have invented and produced a certain new and useful Design for a Badge, of which the following is a specification.

My invention relates to a design for a badge, and is fully shown in the single figure of the accompanying drawing, forming a part of this specification.

The drawing is a view of a badge, showing my new design.

As shown in the drawing, the leading or material features of my design consist of a badge, cylindrical in outline, having thereon the representation of a globe resting on an open book. On the top of the globe is an eagle with outstretched wings. Back of the eagle is a Cuban flag suspended like a ban-

ner. To the right and rear of the globe is draped an American flag, and to the left and rear of the globe is draped the British flag. Across the front of the globe is a key. The 25 face of the globe is designed to receive any motto or legend. Around the outside of the badge is an ornamental border in which any desired name or appropriate device can be inserted.

Having thus described my invention, what I claim as new, and desire to secure by Letters Patent, is—

The design for a badge as herein shown and described.

In witness whereof I have hereunto set my hand and seal in the presence of two witnesses.

THOMAS WILLIAM COSGROVE. [L. S.]
